UNITED STATES PATENT OFFICE

FRANK E. CHAPPER AND WILLIAM R. MCGEE, OF DETROIT, MICHIGAN

BOOT HOOK

Application filed March 25, 1929. Serial No. 349,575.

This invention relates to boot hooks and the object of the invention is to provide a device by means of which rubbers, oxfords, pumps or slippers may be put on the foot.

Another object of the invention is to provide a boot hook by means of which rubbers or low shoes may be put on with the utmost ease and simplicity without the necessity of stooping.

Another object of the invention is to provide a device of the character described in which it is not necessary to handle the footwear while being put on the foot.

A further object of the invention is to provide a device of the character described which may be easily and cheaply manufactured and which is very effective in use.

These objects and the several novel features of the invention are hereinafter more fully described and claimed and the preferred form of construction by which these objects are attained is shown in the accompanying drawings in which—

Fig. 1 is a rear elevation of a boot hook embodying our invention.

Fig. 2 is a side elevation thereof.

Fig. 3 is a section taken on line 3—3 of Fig. 1.

Fig. 4 is a section taken on line 4—4 of Fig. 1.

Fig. 5 is a view showing the use of the device.

The device comprises a sheet metal member provided with a portion 1 which is rolled to fit about the lower end of a wooden handle 2 and is secured thereto by the rivets 3. If desired however, the handle 2 may be formed of sheet metal by rolling the metal so that the portion 1 is continued to provide the handle 2 with the seam at the back. Formed integrally with the portion 1 and extending from one side of the handle 2 is a flat angular portion 4 which is provided with a rib 5 for strength. Depending from the portion 4 is an arcuate portion 6 which is provided with a series of depressions 7 in the concave face thereof as shown in Fig. 4 which form the lugs 8 struck up from the rear or convex side of the portion 6. The handle 2 is provided with an extending pointed end 9 at one side

of the center of the handle as shown in Fig. 2.

While this device is useful in putting on slippers, oxfords, or pumps its greatest use is in putting on rubbers as it eliminates the necessity of handling the rubbers and is especially valuable when the rubbers are dirty, muddy or wet. To put on the rubbers the point 9 is engaged against the rear of the rubber and the rear of the rubber is bent downwardly thereby to spread the opening of the rubber and allow the toe of the shoe to be inserted in the rubber. At this time the portion 6 is moved to position against the rear of the rubber which fits due to its arcuate form and the heel is moved down the portion 4 to the portion 6 at which time by pushing down with the heel of the shoe the shoe will readily move down the portion 6 into the rubber. As the heel is moved into the rubber the portion 6 is engaged between the heel of the shoe and the rear of the rubber thus causing the lug 8 to grip the rubber so that it may be pulled onto the shoe by lifting the handle 2. On account of the thinness of the metal the portion 6 does not take up much room in the rubber and may be readily drawn out from between the rubber and the shoe after the rubber has been put on. It is to be understood that this device may also be used in the same manner for putting on oxfords, slippers or pumps. The end 9 of the device may also be used in taking off the rubbers by pressing down on the rear of the rubber so that the shoe may be drawn out of the rubber.

From the foregoing description it becomes evident that the device is very simple and efficient in operation, will not easily get out of order, is composed of few parts and is of consequent low manufacturing cost, and provides a device which accomplishes the objects described.

Having thus fully described our invention, its utility and mode of operation, what we claim and desire to secure by Letters Patent of the United States is—

1. A boot hook comprising a sheet metal member, a handle provided with a pointed end at one side of the center, the sheet metal member being secured to the handle adjacent the pointed end and extending therefrom on

the side opposite the pointed end, the sheet metal member terminating in a depending portion extending at a slight angle to the longitudinal axis of the handle, the said depending portion being arcuate in cross section and being provided with a series of lugs on the convex surface thereof.

2. A boot hook comprising a handle, a sheet metal member extending at an angle from one side of the handle and having a depending end extending at a slight angle to the handle, the said depending end being arcuate in cross section and being provided with means on the convex surface thereof for engaging the inner surface of the concave heel portion of a rubber or shoe.

3. A boot hook comprising a handle provided with a pointed end, a sheet metal member extending beyond said end from one side of the handle adjacent the pointed end spaced from the pointed end to provide a V notch and having a depending end extending at a slight angle to the axis of the handle, the said depending end being arcuate in cross section.

4. A boot hook comprising a handle, a sheet metal member extending at an angle from the lower end of the handle and having a depending end arcuate in cross section, and a series of lugs on the convex face of the arcuate portion.

5. A boot hook comprising a handle, a sheet metal member secured to the handle and having a depending end beyond the handle end arcuate in cross section, the convex surface of the said end being of a form adapted to grip the inner surface of the curved heel portion of a rubber or shoe.

6. A boot hook comprising a handle, a sheet metal member connected with and extending beyond the end of the handle and having a terminal arcuate portion approximately parallel with the handle and an angularly disposed portion providing a shoulder between the terminal arcuate portion and the angular portion to engage the upper edge of a rubber or other footwear to limit the extent to which the terminal portion may be inserted therein and positioning the handle rearwardly of the rear end thereof, said arcuate portion being provided with gripping portions to engage the rubber or other article whereby as the foot is being inserted therein the operator, by pulling on the handle, may draw the shoe or rubber to final position over the heel.

In testimony whereof we sign this specification.

FRANK E. CHAPPER.
WILLIAM R. McGEE.
